ROLLER SKATE

Frank R. Atkinson, Minneapolis, Minn.

Application September 9, 1940, Serial No. 355,908

4 Claims. (Cl. 301—5.7)

This invention relates to roller skates.

It is an object of the invention to provide a novel and improved roller skate including a single roller structure for the fore part of the skate and a single roller structure for the rear part of the skate.

It is another object of the invention to provide a novel and improved roller structure for roller skates, wherein the roller is supported by roller bearings and wherein the various parts can be readily replaced individually without replacement of other parts.

The objects and advantages of the invention will more fully appear from the following description made in connection with the accompanying drawing, wherein like reference characters refer to the same or similar parts throughout the views, and in which:

Fig. 1 is a plan view illustrating a roller skate for the left foot embodying the invention;

Fig. 2 is a view in side elevation of the skate shown in Fig. 1;

Fig. 3 is a vertical section taken on the line 3—3 of Fig. 2, as indicated by the arrows, the view being in enlarged scale; and

Fig. 4 is a vertical section taken on the line 4—4 of Fig. 3, as indicated by the arrows.

In accordance with the invention there is provided a shoe plate 5 shaped generally to conform to the shape of a shoe, having central strengthening ribs 6 and having an upturned edge flange 7 to give the same additional strength. This plate 5 has a plurality of small apertures 8 therein whereby the plate may be secured as by screws 9 or rivets as to a shoe shown in dotted lines and designated by the letter S. At the point where the ball of the foot and at the point where the heel of the foot will overlie the plate 5, blocks 10 and 11 are respectively employed at the top of plate 5, being of substantially the same thickness as the flange 7.

Fore and aft roller structures are provided for each skate, these structures being identical except for the fact that in the fore structure a pair of brackets 12 are employed which are of somewhat different shape than the brackets 13 used in the aft structure. The brackets 12 and 13 are generally similar, but to properly brace the same the brackets 12 are somewhat longer than the brackets 13.

Referring to the fore roller structure, shown in detail in Figs. 3 and 4, it will be seen that the two brackets 12 oppose each other and are of angular shape, the upper flanges of the brackets being secured as by screws 14 to the block

10 after passing through the plate 5. A bolt 15 extends transversely between the two brackets 12 and is held in place thereon by lock washer 15a and a nut 15b. The bolt to the left of the 5 screw-threaded portion receiving the nut 17, as shown in Fig. 3 of the drawing, is of square shape in cross section and the central part of the bolt is received within a central aperture in a tread cylinder 16, this aperture being square in cross section so that the tread cylinder will not turn on the bolt 15. Between the two ends of the tread cylinder 16 and the brackets 12 are located spacers 17, which are apertured to receive the bolt 15. These spacers space the tread cylinder 16 from the brackets 12.

A sleeve 18 of considerably greater diameter than the diameter of the tread cylinder 16 surrounds the same, and a tire 19 preferably made of rather hard rubber, fibre or comparatively light 20 metal, is carried by the sleeve 18. The sleeve 18 and the tire 19 are of less width than the spacing between the two brackets 12, and abutting the ends of the sleeve and bearing against the sides of the tire 19 are discs 20 and 21. Screws 22 have heads countersunk in the disc 20, project through apertures in the tire 19, and have ends screw-threadedly received within the disc 21.

A plurality of bearing rollers 23 are interposed 30 between the tread cylinder 16 and the sleeve 18, and these rollers have trunnions 24 at their ends which project through trunnion apertures in apertured washers 25 interposed between the discs 20 and 21 respectively and the adjacent 35 ends of the bearing rollers. The extreme outer ends of the trunnions 24 are also received within trunnion grooves 20a and 21a respectively formed in the discs 20 and 21. The discs 20 and 21 and the apertured washers 25 have central openings 40 therein of somewhat less diameter than the diameter of the tread cylinder 16, but of slightly greater diameter than the diameter of the spacers 17, whereby the said spacers may be received within said openings. Of course, the tread rollers 23 bear against the tread cylinder 16 to produce a roller bearing structure, permitting the tire 19, sleeve 18, discs 20 and 21 and washers 25 to readily revolve on the tread cylinder 16.

The tread plates 5 are made in rights and lefts 50 for the different feet of the users and will be secured to the users' shoes. In employing the roller skates, due to the fact that each skate includes only a single roller structure for the fore part of the skate and a single roller structure for the rear part of the skate, a skating

action can be secured highly analogous to the skating action secured when ice skates are employed. In other words, the feet may be tilted readily relative to the surface over which the skater travels to a much greater extent than in the case of the ordinary roller skates where double rollers are employed at the fore part of the skate and double rollers are employed at the rear part of the skate. The corners of the tires 19 are preferably rounded, as shown, to permit of tilting action, and if these tires are made of partially resilient material, such as comparatively hard rubber or fibre, good traction can be obtained to prevent side slippage. The roller bearing structure will cause the rollers of the skates to revolve with great ease without necessitating frequent lubrication. By reason of peculiar construction of each roller structure any of the parts can be easily replaced as they become worn without necessitating replacement of other parts. The tires 19, for example, can be frequently renewed without necessitating renewal of any of the other parts of the skate.

It will be seen that a highly efficient roller skate has been provided of cheap and simple construction.

It will, of course, be understood that various changes may be made in the form, details, arrangement and proportions of the various parts without departing from the scope of the present invention, which, generally stated, consists in the matter shown and described, and set forth in the appended claims.

What is claimed is:

1. In a roller skate, a supporting plate, a pair of roller brackets projecting downwardly from said plate, a cross pin carried by the brackets and extending between the same, a cylinder carried by the cross pin between the brackets, spacers of less diameter than said cylinder interposed between the ends of the cylinder and adjacent brackets and carried by the pin, a sleeve of considerably larger diameter than said cylinder, said cylinder extending through said sleeve, a pair of centrally apertured discs for the sleeve respectively located at the opposite ends of the sleeve, the apertures of said discs being of less

10 diameter than the cylinder and receiving therethrough said spacers, a plurality of cylindrical roller bearing members interposed between said sleeve and said cylinder, and an annular tire secured to said sleeve.

2. The structure defined in claim 1, said cylindrical roller bearing members having trunnions on their ends, and apertured washers receiving said trunnions and interposed between said discs and said roller bearing members.

3. The structure defined in claim 1, said cylindrical roller bearing members having trunnions at their ends, apertured washers receiving said trunnions, said washers being interposed between said discs and said roller bearing members, and said discs having circular grooves therein within which the outer ends of said trunnions are received.

4. In a roller skate, a supporting plate, a pair 20 of opposite brackets projecting downwardly from the plate, a cross pin of polygonal shape mounted in and extending between the brackets, a cylinder having a transverse opening therethrough of polygonal shape and located between the two 25 brackets and receiving said pin, a pair of spacers of less diameter than the cylinder interposed between the ends of the cylinder and the adjacent brackets, a sleeve of considerably greater diameter than said cylinder and receiving the cylinder within the same, an apertured disc at each end of said sleeve, the apertures in which discs are smaller in diameter than the diameter of said cylinder and which disc apertures receive said spacers, an annular tire within which 30 said sleeve is received, means extending between said discs and projecting through said tire for securing the tire in position, a plurality of cylindrical roller bearing members interposed between said sleeve and said cylinder, said roller bearing members having projecting trunnions at their ends, and a plurality of apertured washers interposed between said discs and said roller bearing members and receiving said trunnions 35 therein, said discs having circular grooves in their inner sides receiving the inner ends of 40 said trunnions.

FRANK R. ATKINSON.
